VOLTAGE REGULATOR

Gerald Diepenhorst, Romulus, and Marvin S. Dunenfeld, Ann Arbor, Mich., assignors to Ford Motor Company, Dearborn, Mich., a corporation of Delaware

Application January 7, 1957, Serial No. 632,779

8 Claims. (Cl. 200—102)

This invention pertains to a voltage regulator which is especially adaptable to a motor vehicle electrical system.

In the conventional voltage regulator there are three cores and three windings in order to provide the generator from exceeding a maximum voltage and current value and also to prevent the battery from discharging into the generator. With this invention the same functions are performed but a core has been eliminated resulting in a space and cost saving.

This invention and its objects and advantages will be better understood when a preferred embodiment is discussed in connection with the drawings in which:

Figure 1 is a schematic drawing of the electrical circuit used in the preferred embodiment; and

Figure 2 is an elevational partially broken away view of a core which has two windings and two switches connected therewith.

In Figure 1 is seen the circuit which makes possible the use of only two cores in a motor vehicle voltage regulating system while still performing the functions of a three core system. Connected between the armature of generator 21 and field 22 is field limiting resistance 24 which may have a value of 120 ohms for a 12 volt 38 ampere generator and this resistance is bypassed by switches 27-1 and 29-1 which are opened respectively by excessive voltage across shunt voltage relay 27 and excessive current through series current winding 29. Resistance 31 which may be 50 ohms is connected between the field circuit and ground. Switch 28-1 is closed by shunt voltage windings 28 when the armature voltage is equal to or greater than a predetermined voltage which may be between 12 and 12.8 volts. It is seen that windings 28 and 29 are wound on core 32. Battery 23 is shown connected to relay 29 with the rest of the vehicle electrical circuit not being shown.

Figure 2 illustrates a possible construction for having two windings on the same core. Core 32 has wound about it voltage coil 28 which has many turns of fine wire and about coil 28 is wound current coil 29 which has a few turns of heavy wire. Hinged to core housing 36 through member 38 is magnetic arm 37 which closes the contacts for switch 28-1. Member 38 may be bimetallic so that during cold ambient temperatures switch 28-1 will close later under a higher voltage than during a warmer ambient temperature because higher voltages are needed in cold weather. Fastened to arm 37 are contacts for switch 29-1 with the lower portion of the lower contact extending through opening 39 in arm 37. Contacts 29-1 are normally closed with the lower contact being held by bimetallic hinge 41 so that during cold ambient temperatures the generator field will have resistance 24 thrown in at a higher current.

In the operation of this embodiment switch 28-1 re-

2

mains open until a minimum voltage has been developed by the generator armature. By making this voltage higher than the battery voltage, battery discharge into the generator will be prevented. The closing of switch

5 28-1 is done by arm 37 being drawn downwardly by a certain value of the magnetic field of core 32 which is established by the winding of voltage coil 28. Now as the armature voltage and current increase above predetermined maximums which may be 15 volts and 30 amperes

10 switch 27-1 and/or 29-1 is opened putting resistance 24 into the field circuit decreasing the generator output. Voltage relay coil 27 may be of conventional design while current relay coil 29 is wound about voltage coil 28 and when the combination of field strengths established by coils 28 and 29 reaches a predetermined value

15 the lower contact of switch 29-1 which is connected to magnetic disc 33 is pulled away from the upper contact throwing in resistance 24 to the field circuit. In this embodiment the value at which the current will open switch 29-1 will be 30 amperes at 15 volts and 32.5 amperes at 12 volts.

It will be understood that this invention is not to be limited to the exact construction shown and described, but that various changes and modifications may be made without departing from the spirit and scope of the invention as defined in the appended claims.

What is claimed is:

1. In a voltage regulator that improvement comprising a core having two windings and two switches, a first switch being hinged at one end of said core and a second switch being hinged to said first switch, said first switch defining a flux path opening, a portion of said second switch extending through said opening so that after said winding and core have established a predetermined field said second switch will be opened.

2. In a combined cutout relay and current regulating mechanism wherein a cutout relay coil and a current coil are wound on a single magnetic core that improvement comprising a cutout contact actuating armature operably positioned in the flux path of said core, said contact actuating armature defining an opening therein within the region of said flux path, a current-limiting contact actuating armature mounted on said first-named armature and positioned over said opening to be actuated by flux through said opening.

3. The mechanism of claim 2 wherein said second-named armature is actuated by a substantially increased flux density over the amount required to actuate the first-named armature.

4. In a magnetic relay having a wire wound core, that improvement comprising a first contact carrying armature operably positioned in the flux path of said core, said first armature defining an opening therein within the region of said flux path, a second contact carrying armature positioned over said opening to be operated by flux from said core through said opening.

5. The device as in claim 4 wherein said second armature is carried by said first armature.

6. The device as in claim 4 wherein said second armature is bimetallic.

7. The device as in claim 4 wherein said second armature includes a portion extending into said opening.

8. In a combined cutout relay and current-regulating mechanism wherein a cutout relay coil and a current coil are wound on a single magnetic core that improvement comprising a cutout contact actuating armature oper-

ably positioned in the flux path of said core, said contact actuating armature defining an opening therein in the region of said flux path, and a current-limiting contact actuating armature positioned over said opening to be actuated by flux therethrough.
